UNITED STATES PATENT OFFICE.

ALEXANDER HOSTETTLER, OF COLUMBUS, OHIO.

BOTTLE-SEALING DEVICE.

No. 878,287.

Specification of Letters Patent.

Patented Feb. 4, 1908.

Application filed July 22, 1907. Serial No. 384,990.

To all whom it may concern:

Be it known that I, ALEXANDER HOSTETTLER, a citizen of the United States, residing at Columbus, in the county of Franklin and State of Ohio, have invented a certain new and useful Improvement in Bottle-Sealing Devices, of which the following is a specification.

As at present in extensive use the seals or stoppers for bottles, especially beer bottles, comprise a metallic cup-shaped cap containing in its bottom a flat disk of cork, said cap in practice being pressed down and pinched inward around its edges to engage an annular projection around the neck of the bottle near its rim. Such devices are commonly known as crown seals and they are used in connection with what are known as "crown bottles"; that is, bottles having a shoulder on the outer side of the neck near its top. It is a matter of general experience, and especially with bottlers of beer, that bottles designed to receive such cap seals frequently have their rims or necks more or less chipped, due to rough handling and to the defective use of devices for removing the seals. This is the occasion of serious loss, because with bottles having chipped or otherwise defective necks it is impracticable to use the seal as now constructed. A chipping or defect in the neck of the bottle, which, of course, coöperates with the cork of the sealing device, renders it ordinarily impracticable, with the seal as at present constructed, to secure a tight, perfect closure, hence defective bottles are culled out as useless. In bottling beer it is customary to test every bottle after it is sealed to ascertain its tightness, and the present practice develops that even with apparently perfect bottles a considerable proportion are found defective, due not only to the existence of unobserved defects in the bottles but also to insufficiency of or defects in the sealing device itself.

The object of the present invention is to provide an improved device of the kind generally referred to by which a perfect sealing may be insured and by which most of the defects in the bottle now regarded as fatal may be ignored.

The invention consists in the construction hereinafter described and then particularly pointed out in the claims, the invention not being confined in its embodiment to the precise forms herein shown and described.

In the accompanying drawings illustrating

the preferred embodiment of the invention, Figure 1 is a plan view looking at the under side or interior of the seal; Fig. 2 is a view showing the metallic cap portion in diametrical section and the sealing portion in full; Fig. 3 is a sectional view showing the sealing device as applied to the neck of a bottle.

In the views the character 4 designates a metallic cap having a crimped edge or flange 4^a as is usual in what are now commonly known as "crown" seals. Within this is placed a cork sealing or stoppering member comprised of a single integral piece cut to form a cylindrical disk or circular base portion 5 with a centrally-projecting cylindrical portion 6 of smaller diameter than that of the base portion 5. The cork member thus formed provides an annular horizontal sealing surface 5^a that engages the rim of the neck of the bottle, and a vertical surface 6^a forming a plug-like member that enters the mouth of the bottle and engages the inner wall thereof, as seen in Fig. 3. There are thus primarily provided by the cork two sealing surfaces, one around the top of the rim and one around the interior of the mouth of the bottle, but because of the cylindrical form of the two portions thereof, the device can be pressed into close engagement with the bottle all the way from the interior of the neck to a line at the outer side thereof below the top of the mouth of the bottle and even though the junction between the surfaces 5^a and 6^a be angular. But said junction can be made primarily rounding if desired. In practice the central projecting portion 6 will preferably be made of no greater thickness than that of the disk or base portion, and for the standard beer bottle the said parts will each be about one-eighth of an inch in thickness or the cork portion have a total thickness of one-fourth inch. The diameter of the base 5 is such as to fit and be held by friction in the metallic cap, and the diameter of the projection 6 is such that it will enter and suitably engage the inner side of the mouth of the bottle. In the instance shown the flange or edge of the metallic cap extends below the edge of the disk portion and in practice is pressed or clenched inward under the outwardly-projecting shoulder 7 near the rim of the bottle as usual.

My invention is not confined in its use to the form of cap or device shown for holding the compressible sealing member, as other forms of devices for performing this function

can be employed. Nor do I limit myself to the use of cork, because any other compressible material or combination of materials forming a material adapted to be molded or shaped into substantially the form shown can be employed. I prefer the use of cork, however, because I have discovered that in my particular form of sealing device it is, among other advantages, more freely compressible than paper, and when pressed into position it tends more to retain its compressed position than rubber.

The embodiment of my invention herein particularly described can be applied to and removed from bottles by the same means as are now used for those purposes in connection with the ordinary so-called crown seals now on the market.

What I claim and desire to secure by Letters Patent is:

1. A bottle sealing device comprising, in combination, a compressible member consisting of a single integral solid piece of cork formed as a flat cylindrical portion 5 with a cylindrical portion 6 of smaller diameter projecting from one face thereof, the axes of said cylindrical portions coinciding in the same straight line, and a metallic cap including

integrally therewith a circumferential pendent flexible flange, said cap containing said compressible member, and said flange adapted to be pressed inward at its lower edge to engage a shoulder on the outer side of the neck of the bottle at its top, and said cork being of a thickness approximately equal the depth of the cap.

2. A bottle sealing device comprising, in combination, a compressible member consisting of a single integral solid piece of compressible material formed as a flat cylindrical portion 5 with a cylindrical portion 6 of smaller diameter projecting centrally from one face thereof, the axes of said cylindrical portions coinciding in the same straight line, and a metallic cap including integrally therewith a circumferential pendent flexible flange said cap containing said compressible member, and said flange adapted to be pressed inward at its lower edge to engage a shoulder on the outer side of the neck of the bottle at its top, and said cork being of a thickness approximately equal the depth of the cap.

ALEXANDER HOSTETTLER.
